(57) **CLAIM**

The ornamental design for a shelf for histologic device for biological samples, as shown and described.

DESCRIPTION

FIG. 1 is a top right front isometric view of a shelf for histologic device for biological samples showing the new design;

FIG. 2 is a front view thereof;

FIG. 3 is a rear view thereof;

FIG. 4 is a right side view thereof, with the left side view being a mirror image;

FIG. 5 is a top view thereof;

FIG. 6 is a bottom view thereof;

FIG. 7 is a bottom left front isometric view thereof;

FIG. 8 is an enlarged view of area 8 shown in FIG. 1;

FIG. 9 is an enlarged view of area 9 shown in FIG. 7; and, FIG. 10 is a cross sectional side view taken from line 10-10 shown in FIG. 2.

The dashed lines in the drawings depict portions of the shelf for histologic device for biological samples that form no part of the claimed design.

The dot-dash lines shown in the drawings depict symbolic break lines that form no part of the claimed design, and any portion between the dot-dash lines form no part of the claimed design.
